NARROW WARE LOOM

Elbridge R. Holmes, Worcester, Mass., assignor
to Crompton & Knowles Loom Works, Worcester, Mass., a corporation of Massachusetts

Application April 22, 1949, Serial No. 89,006

13 Claims. (Cl. 139—136)

1

This invention relates to narrow ware looms and it is the general object of the invention to provide such a loom wherein normally stationary shuttle blocks are mounted so they can be swung forwardly to facilitate mending a broken warp thread.

The invention relates more particularly to the type of narrow ware loom wherein the reed dwells at back center and is moved forwardly for beat-up after the shuttle has moved from one stationary shuttle block to another similar block. When stationary shuttle blocks are used it is desirable that they be in rearward position so that the shuttles may pass through the sheds, but when the blocks are in this position they are close to the harness frames and it is difficult to reach a broken warp thread.

In order to facilitate the mending of a broken warp thread in this type of narrow ware loom it is an important object of the invention to mount the shuttle blocks so that when required they can be swung forwardly away from the harness frame, thereby making a broken warp thread more accessible.

In order that the driving connections for the shuttles may remain intact when the shuttle blocks are moved forwardly it is a further object of the invention to actuate the rack rod by a chain or another form of flexible connector which is preferably coaxial with the center around which the shuttle blocks are swung. The rack rod turns with the shuttle block and is connected to the flexible actuator by a rotatable connector.

In order to prevent operation of the loom when the shuttle blocks are in an abnormal forward position it is a further object of the invention to provide a form of lock which will hold the shuttle blocks in their normal stationary weaving position so long as the loom is in operation. The lock is so controlled that it can be moved to permit forward motion of the shuttle blocks only when the loom is stopped. The control is also connected in such manner that the loom cannot be started while the shuttle blocks are in their abnormal forward position.

It is a further object of the invention to operate each reed by mechanism located between adjacent shuttle blocks and in such position as will permit forward movement of the shuttle blocks. The reed actuating mechanism preferably rocks on two pick time, each motion of the mechanism corresponding to a beat-up.

With these and other objects in view which will appear as the description proceeds, the in-

2

vention resides in the combination and arrangement of parts hereinafter described and set forth.

Fig. 1 is a side elevation of part of a loom made according to the present invention,

Fig. 2 is a front elevation looking in the direction of arrow 2, Fig. 1, parts being in section and parts broken away,

Figs. 3 and 4 are enlarged vertical sections on lines 3—3 and 4—4, respectively, Fig. 2,

Fig. 5 is an enlarged vertical section on line 5—5, Fig. 2,

Fig. 6 is an enlarged side elevation looking in the direction of arrow 6, Fig. 2,

Fig. 7 is a detailed horizontal section on line 7—7, Fig. 6,

Fig. 8 is a fragmentary vertical section on line 8—8, Fig. 7,

Fig. 9 is an enlarged vertical section on line 9—9, Fig. 7, and

Fig. 10 is a vertical section on line 10—10, Fig. 6, showing the loom driving control mechanism and part of the locking means in two positions.

Referring particularly to Figs. 1 and 2, the loom frame comprises right and left loom sides 10 and 11 between which extends a shaft 12 rotating on two pick time. A take-up roll 13 and driving mechanism therefor actuated by a crank 14 on shaft 12 may be of usual construction and advances the several webs which are woven in the loom, one of these webs being indicated at F. The loom has harness mechanism of the usual type designated herein diagrammatically by harness frames 15 which form the warp shed W.

Shuttle operating chains or flexible actuators 16 and 17 are located respectively at the right and left of the loom and are operated by any suitable form of mechanism which operate the chains to move the shuttles in one direction on one pick of the loom and in the opposite direction on the next pick of the loom. Such mechanism is not shown specifically herein, but may be similar to that shown in my prior Patents 1,668,150 and 1,766,903, with the exception that in the patents the chains rock back and forth with the lay, whereas herein there is no reciprocating lay and the chains move in a fixed plane.

The matter thus far described, except as already noted, may be of common construction and operate in the usual manner.

The present invention provides a series of normally stationary blocks which can be rocked

forwardly and also provides beat-up reeds which dwell in rear position during movement of the shuttles through the warp sheds and then have a quick beat-up and return to rear position for the next passage of the shuttles. The shuttle block structure will be described first, after which the mechanism for operating the reeds will be described.

Referring particularly to Fig. 2, it will be seen that loom sides 10 and 11 have secured thereto support brackets 20 and 21, respectively, held in fixed position on their respective loom sides, as by bolts 22, see Fig. 6. Each support is provided with a bearing 23 and a cap 24 to provide pivotal mounting for a tubular support member or carrier 25. This support member may be in the form of a pipe extending across the loom and mounted for turning about its axis in the bearings.

Ordinarily turning of the tube 25 will be prevented by means of a lock mechanism including a segment or locking member 26 clamped as at 27 to the tube and having a lock slot or notch 28 located therein to receive a lock tooth 29. The lock tooth is on a control lever 30 pivoted as at 31 to the support 20 at the right hand side of the loom, see Figs. 2 and 6. A heavy tension spring 32 interposed between the forward end of lever 30 and a fixed stud 33 on loom side 10 normally holds lock lever 30 in the down full line position shown in Fig. 6 with the lock tooth in slot or notch 28. Under these conditions the tubular support cannot rock in its bearings and is held stationary.

The loom driving control mechanism includes a shaft 35 rockable in front and back bearings 36 and 37 secured to the loom side 10. The forward end of this shaft has secured thereto an upright arm 38 connected to a shipper rod or bar 39 extending across the loom. The rear part of shaft 35 is connected to usual well known loom driving mechanism not shown herein. It is thought sufficient for present purposes to state that when shaft 35 is rocked counterclockwise, Fig. 2, the loom will be stopped, but when shaft 35 is rocked clockwise the loom will operate.

Secured to shaft 35 is a second segment or locking member 40 having a slot or notch 41 which is adapted to receive the rear end of arm 42 of lever 30. When the loom is running the segment 26 and the lock tooth 29 will be in the full line positions shown in Fig. 6 to lock tube 25 in stationary position, and the unnotched part of segment 40 will be under lever arm 42 to prevent the latter from moving downwardly, as shown in dotted lines, Fig. 10. So long as the loom is in operation with shaft 35 in operating position to locate the second lock member 40 in the dotted line position of Fig. 10, the tubular member 25 cannot be rocked in its bearings. When the loom is stopped, however, movement of shaft 35 to stopping position suggested in full lines in Fig. 10 will locate slot or notch 41 under lever arm 42 and the latter can if desired be lowered by manual rocking of lever 30 to the dotted line position shown in Fig. 6 against the action of spring 32 to disengage tooth 29 from notch 28 and cause lever arm 42 to enter notch 41. If member 25 is rocked under these conditions, segment 26 will rock to the dotted line position of Fig. 6 with its arcuate surface 43 in position to engage the locking tooth 29 and prevent the lever arm 42 from being moved upwardly by spring 32 out of notch 41. The lever arm 42 is thus held in notch 41 to prevent start-

ing of the loom so long as the segment 26 and tubular member 25 are unlocked. A stop lug 44 on segment 26 engages lock tooth 29 to limit counterclockwise rocking of segment 26, see Fig. 6.

Arranged along and secured to the member 25 is a series of shuttle blocks, four of which are shown in Fig. 2, at B1, B2, B3 and B4. Each shuttle block is secured to a block carrier 45 the lower part of which 46 is split and surrounds the tube 25 and is clamped thereto as at 47. Each block support 45 has a front wall 48 and a higher wall 49, the associated shuttle block being held between the walls.

Each shuttle block has rotatable thereon top and bottom meshing pinions 50 and 51, respectively, the latter extending downwardly through a slot 52 in the upper part of the tube 25. The upper pinion has driving relation with first one and then the other of two shuttles with which it cooperates. Three shuttles are shown at S1, S2 and S3 in Fig. 2. These shuttles are of the circular type and move back and forth in the usual manner in grooves 55 in the shuttle blocks. It is not thought necessary to describe the manner in which rotation of the pinions causes the shuttles to pass from one block to a neighboring block, since the blocks, shuttles and pinions operate in the usual and well known manner.

The lower pinions 51 mesh with a shuttle actuator or rack rod 53 in a guide or filler 57 within the tube 25 and secured thereto against longitudinal movement as by screws 58. The guide 57 may be made of wood and has a slot 59 in which the rack rod slides. Reciprocation of the rack rod within the tube 25 causes turning of the pinions 50 and 51 with accompanying motion of the shuttles.

The ends of the rack rod have driving relation with the previously described actuator chains 16 and 17 by rotatable fittings which are the same for each end of the loom. One of these fittings will be described in connection with Figs. 7, 8 and 9. The rack rod has an enlarged head 60 slideable along a reduced arm 61 of the filler 57. This head 60 has attached thereto a U-shaped sheet metal member 62 having parallel sides 63 and 64 joined by a cross plate or end 65. The head is secured as by pins 66 to the side plates 63 and 64.

As shown in Fig. 7 a washer 70 engaging the left face of the end plate 65 engages a right hand race 71 of a ball bearing designated generally at 72 and having a left hand race 73 bearing against another washer 74. A stud or chain head 75 passes through and is rotatable in the washers 70 and 74 and the ball bearing 72 and has threaded on the left hand end thereof nuts 76 one of which is against washer 74 and the other of which is a lock nut. The right end of the head or stud 75 extends beyond or to the right of the U-shaped member 62 and is connected as at 77 to the adjacent end link 18 of chain 16.

The connection between the left end of the rack rod and chain 17 is the same as that already described, and when the nuts 76 of both connections are tightened to take up slack between the chains and the rack rod movement of the chains will cause longitudinal motion of the rack rod within the tube 25, the end forces being exerted through the ball bearings 72. When the tubular member 25 is unlocked as already mentioned and turned in its bearings the ball bearing 72 turns to accommodate the angular motion of the tube 25 without twisting the chains.

It will be seen from Fig. 1 that the shuttle blocks are close to the harness frames 15 and since they are normally locked stationary in the upright position shown in Fig. 1 it would be difficult for the weaver to reach behind the blocks to mend a broken warp thread. It is for this reason that the tubular member 25 and the shuttle blocks are mounted so that they can swing forwardly from the full line to the dotted line position shown in Fig. 6.

As shown in Fig. 2 each of the chains 16 and 17 is trained over a sprocket 33 mounted on the upper end of a link 21 which may be similar to a link shown in the previously mentioned Patent 1,766,903. Each of the sprockets 33 is spaced from the tubular support 25 by a rod 32 having a screw threaded end 33 tapped into the corresponding support 26 or 24 and held in adjusted position by a lock nut 34. The rods are thus adjustable to permit movement of the sprocket for the purpose of tightening the chain.

The movable support for each reed registers with the space between the corresponding shuttle blocks to enable the latter to swing forwardly without interference, as will be apparent from Fig. 2.

Secured to shaft 12 is a grooved cam 85 having a high dwell 86, a low dwell 87, and two inclines 88 and 89. A roll 90 fits into the groove and is rotatable on an actuator arm 91 having a slot 92 which receives the shaft 12, see Fig. 5. As shown in Fig. 1 the forward end of the actuator 91 has adjustably secured thereto a rod 93 connected to an arm 94 secured to a rock shaft 95. The latter is mounted for oscillation in the stands 20 and 21 and also in intermediate stands 96 each supported on two struts 97 and 98. The shaft 95 extends across the loom so that it can be operatively related to a number of different reeds.

A reed holder 99 is supported by the upper ends of the arms corresponding to a reed space 100 between the shuttle blocks. Each reed is mounted on a holder 99 supported by four arms arranged in two pairs. As shown in Figs. 3 and 4 two rods 101 and 102 are mounted for rocking in end supports 20 and 21 and also the intermediate supports 96. Two arms 103 are secured at 104 to rod 101, and similarly two arms 105 are secured at 106 to rod 102. These pairs of arms support the holder 99 for parallel motion. The rear end of the holder extends upwardly as at 110 and cooperates with a lock bar 111 to hold the lower end of reed R fixed with respect to the holder. A set screw 112 clamps the lock bar against the reed to hold the latter in the upright position shown for instance in Fig. 4.

Extending between the arms 105 is a pin 115 pivotally attached to a connector 116 the rear end of which is pivoted to a crank arm 117 secured to a shaft 95 as at 118. The shaft 95, connector 116 and crank arm 117 constitute an operating means for the pairs of arms 103 and 105, while the said arms and the holder 99 are the operating mechanism for the reed.

The cam 85 and the rack rod are so timed that one or the other of the dwells 86 or 87 will hold the reed R in normal position behind the path of the shuttles while the latter are moving, and after the shuttle motion is completed in one direction the cam acting by one or the other of its inclines 88 or 89 will rock shaft 95 from one of its extreme positions to its other extreme position, thereby moving the arms 103 and 105, holder

99, and reed R first forwardly to the full line beat-up position shown in Fig. 4 and then back to the rear dotted line position. When shaft 95 rocks in the opposite direction the reed is given a second beat-up motion.

It will be understood that there will be one reed for each of the fabrics F and that the extent of motion of the reed can be varied by changing the adjustment of a stud 120 in a slot 121 in arm 104. Each reed R, its holder 99, and arms 103 and 105 register with the corresponding reed space 100 so that the shuttle blocks can move to the dotted line position shown in Fig. 6 without striking or interfering with the reeds or their mountings. The loom can be stopped with the reed in any position and the shuttle blocks will be able to swing forwardly.

From the foregoing it will be seen that the invention sets forth means by which a series of shuttle blocks in a narrow ware loom are normally stationary but are so mounted that they can swing forwardly away from the harness frames to facilitate the mending of a broken warp thread. It will also be seen that the loom shipper mechanism and the tubular member 25 are intercontrolled by lock lever 33 in such manner that the shuttle blocks cannot be swung forwardly so long as the loom is in operation, nor can the loom be started if the shuttle blocks are in their forward non-weaving position. Also, the rotary connection between the chains and the rack rods permit the tube 25 to be rocked without straining the chains 16 or 17. Furthermore, the reeds are mounted on parallel arms registering with reed spaces between the shuttle blocks so that the latter can swing forwardly without interference on the part of the reed or any part of its operating mechanism.

Having thus described the invention it will be seen that changes and modifications of the foregoing specific disclosure may be made without departing from the spirit and scope of the invention.

What is claimed as new is:

1. In a narrow ware loom having warp controlling harness frames, a series of aligned shuttle blocks forward of the harness frames mounted as a group to be either in stationary normal weaving position adjacent to the harness frames or in non-weaving position forward of the normal position thereof and the harness frames, means locking said group in stationary normal position during loom operation, loom driving control mechanism in one position when the loom is operating and in another position when the loom is stopped, and a lock member for the locking means positioned by the control mechanism when the latter is in said one position preventing the locking means from unlocking said group during loom operation but positioned by the control mechanism when the latter is in said other position incident to loom stoppage to permit the locking means to move to unlocking position to enable said group to move to said non-weaving position thereof.

2. In a narrow ware loom having warp controlling harness frames, an elongated support member extending across and mounted on the loom in front of said harnesses for angular motion about an axis fixed with respect to the loom, shuttle blocks secured to and extending upwardly from and movable angularly with said support member about said axis, a lock normally holding the member and shuttle blocks stationary with respect to the loom with the shuttle

blocks adjacent to said harness frames, and means preventing the lock from moving to unlocking position relative to the member when the loom is in operation but permitting the lock to move to unlocking position relative to the member when the loom is stopped to permit angular movement of the upper ends of said shuttle blocks around said fixed axis forwardly away from said harness frames.

3. In a narrow ware loom having loom driving control mechanism in operating position when the loom is running and in stopping position when the loom is stopped, an elongated member extending across the loom, shuttle blocks fixed to said member, means mounting the member for angular motion about a fixed axis to move the shuttle blocks forwardly from the normal position thereof, lock means controlled by the loom control mechanism and caused by the latter to prevent angular motion of said member and shuttle blocks and to hold the latter in normal stationary position during loom operation and enabling the lock means to move to unlocking position relatively to the member to permit angular motion thereof only when the loom control mechanism is in stopping position.

4. In a narrow ware loom having a series of shuttle blocks, a support for said blocks mounted on the loom for angular movement about an axis, a rack rod for operation of shuttles on the blocks extending along said axis and moving angularly with the blocks, a reciprocating actuator for the rack rod moving in a fixed plane, and a connection between the rack rod and actuator having a part secured to the rack rod and a second part secured to the actuator, one of said parts being rotatable on the other part and said parts cooperating to cause the actuator to move the rack rod.

5. In a narrow ware loom having a series of shuttle blocks, a tubular member to which the shuttle blocks are secured, bearings on the loom in which the member is movable angularly about the axis thereof to rock the shuttle blocks from the normal position thereof, a rack rod within and moving angularly with said member and movable longitudinally to operate shuttles on the shuttle blocks, a reciprocating actuator for the rack rod, and a connection between the rack rod and actuator causing the latter to move the rack rod longitudinally and enabling the rack rod to move angularly relatively to the actuator when the tubular member turns in said bearings.

6. In a narrow ware loom having a control mechanism in operating position when the loom is running and in stopping position when the loom is at rest, a series of shuttle blocks, a support to which the shuttle blocks are secured movable about a fixed axis, a locking member moving with said support, said shuttle blocks, support and locking member normally in stationary position with the shuttle blocks in a weaving position but movable angularly about said axis to place the shuttle blocks in a non-weaving position, a second locking member moving with the control mechanism, and a lock for cooperation with one or the other of said locking members, said lock normally having locking relation with the first named locking member to lock the shuttle blocks in stationary weaving position and being prevented from moving to unlocked position relative to said first member by the second locking member when the control mechanism is in operating position, said lock being movable out of locking relation with respect to the first

locking member and into locking relation with respect to the second locking member only when the control mechanism is in stopping position, and the first locking member preventing said lock from moving out of locking relation with respect to the second locking member when the shuttle blocks are in non-weaving position.

7. In a narrow ware loom, a series of shuttle blocks, a support to which said shuttle blocks are secured movable about a fixed axis, said blocks and support being normally in stationary weaving position and rockable about said axis to move the blocks to non-weaving position, loom control mechanism movable either to running or stopping position, and locking means including a locking member fixed with respect to said support and a second locking member fixed with respect to said control mechanism and a lock for cooperation with said locking members, said locking means preventing the lock from unlocking the locking member for the support unless the locking member for the control mechanism is in stopping position and preventing the lock from moving out of locking relation with respect to the second locking member unless said support and shuttle blocks are in normal position.

8. In a narrow ware loom, a pair of shuttle blocks separated by a reed space, a support to which the shuttle blocks are secured rockable about a fixed axis and normally held stationary with the shuttle blocks in weaving position but capable of moving angularly to move the shuttle blocks forwardly, a reed in said reed space, and operating mechanism forward of said reed located within a space registering with said reed space to reciprocate the reed, said operating mechanism being out of the path of said shuttle blocks when the latter move forwardly.

9. In a narrow ware loom, a pair of shuttle blocks separated by a reed space, a support on which the shuttle blocks are fixed supported on the loom and normally held in fixed position with the shuttle blocks stationary in weaving position but movable to move the shuttle blocks forwardly, a reed in said reed space, parallel arms movable about spaced axes supporting the reed, and operating means moving said arms about their respective axes to move the reed forwardly for a beat-up, said arms being confined to a space in front of and registering with said reed space to be out of the path of said shuttle blocks when the latter move forwardly.

10. In a narrow ware loom operating with a plurality of shuttles and having warp harness frames, an elongated support member extending across the loom and mounted to move angularly around an axis fixed with respect to the loom, a plurality of shuttle blocks for the shuttles fixed to and extending upwardly from said support member, an actuator for the shuttles extending coaxially with respect to said support member, and lock means for said member capable of assuming two positions in one of which said lock means locks the support member and shuttle blocks in normal position fixed with respect to the loom, said member and upper parts of said shuttle blocks being movable angularly around said axis and actuator to move the shuttle blocks away from said harness frames when the lock is in the other position thereof.

11. In a narrow ware loom operating with a plurality of shuttles and having warp harness frames, a tubular support member mounted to move angularly about an axis fixed with respect to the loom, a plurality of shuttle blocks secured

to and extending upwardly from the tubular member, a shuttle actuator extending through and coaxial with said tubular member, and lock means capable of assuming locking and unlocking relation with respect to said tubular member effective when in locking relation to hold said tubular member and shuttle blocks stationary with respect to the loom and the upper parts of said shuttle blocks being movable forwardly around said axis away from the harness frames when said locking means is in unlocking relation relative to said tubular member.

12. In a narrow ware loom operating with a plurality of shuttles and having warp harness frames, an elongated support member extending across the loom and mounted for angular movement about an axis fixed with respect to the loom, a plurality of shuttle blocks secured to and extending upwardly from and arranged along the support member, shuttle operating pinion means rotatable on each shuttle block, a shuttle actuating rack coaxial with the support member meshing with said pinion means, and lock means capable of assuming locking and unlocking relation relative to said support member and effective when in locking relation to hold said member and shuttle blocks fixed in normal position, said support member being capable of angular movement about said axis in a direction to move the upper parts of said shuttle blocks away from said harness frames when the locking means is in the unlocking position thereof relative to the support member.

13. In a narrow ware loom operating with a

plurality of shuttles and having warp harness frames, an elongated support member mounted for angular motion about an axis fixed with respect to the loom, a plurality of shuttle blocks for the shuttles secured to said support member and separated by spaces arranged along said support member, a reed for each of said spaces movable forwardly from a normal position to a beat up position forward of the shuttle blocks 10 when the latter are in normal position, and lock means capable of assuming locking and unlocking positions relative to the support member effective in locking position to hold said support member and shuttle blocks stationary in normal 15 position, said shuttle blocks being movable angularly about said axis forwardly relative to said harness frames when the lock means is in the unlocking position thereof relative to the support member, whether the reeds be in normal or beat-up position.

ELBRIDGE R. HOLMES.
